(57) **CLAIM**

I claim the ornamental design for a label for control panel, as shown and described.

DESCRIPTION

FIG. 1 is a front elevational view of a label for control panel showing my new design; and,

FIG. 2 is a front end view of the label for control panel in accordance with my design, shown in its environment thereof.

The broken lines are for the purpose of illustrating environmental structure and form no part of the claimed design.
